METHOD OF AND APPARATUS FOR FORMING
SHEET MATERIAL

Arthur E. Collins, Cuyahoga Falls, Ohio, assignor
to The B. F. Goodrich Company, New York,
N. Y., a corporation of New York

Application May 7, 1937, Serial No. 141,286

20 Claims. (Cl. 154—30)

This invention relates to methods of and apparatus for forming sheet material, and is especially useful in the forming of pleats in unvulcanized or partially vulcanized sheet rubber or similar plastic material. For example, the invention is applicable to the making of the pleated sheet material disclosed and claimed in the co-pending application of Mary Hajoway, Serial No. 119,420, filed January 7, 1937.

10 The principal objects of the invention are to provide economy, efficiency, and precision of operation and uniformity of product, and to provide for variation of design in the finished material.

15 Other objects will appear from the following description and the accompanying drawings.

Of the drawings:

Fig. 1 is a plan view of the apparatus in its preferred form, showing the partially formed sheet of material, parts being broken away and parts shown in section to reveal the mechanism.

20 Fig. 2 is a sectional elevation, taken on line 2—2 of Fig. 1, showing one end of the apparatus, the other end being broken away.

25 Fig. 3 is a sectional detail view, taken on line 3—3 of Fig. 2.

Fig. 4 is a detail perspective view of one of the eccentric shafts.

Fig. 5 is a side elevation of the apparatus, part 30 of the gear housing being broken away.

Fig. 6 is a detail view similar to Fig. 3, but showing the sheet material, the feed belt, and its supporting anvil plate, in the position assumed by the parts in adhering the sheets to the belt as 35 the initial operation of forming a pleat.

Fig. 7 is a similar view showing the parts in the positions they assume in adhering the sheet to itself to complete the pleat.

Fig. 8 is a detail view of the ratchet feed 40 mechanism.

The apparatus of the illustrative embodiment generally comprises a pair of pressing members between which the sheet material is fed into engagement with a conveyor-belt, with means for alternately pressing the members toward the belt, the movements of the members being directed with relation to the belt so that each crosses in its pressing movement the path of the other in its alternate pressing movement, the conveyor belt 45 being advanced between sets of pressing movements and the sheet material being temporarily adhered to the belt in pleated form.

50 Referring to the drawings, the numeral 10 designates the frame of the machine, on which a round table 11 is rigidly supported. This table

rotatably supports a frame 12 having a rigid metal top plate 13. Frame 12 is pivotally mounted at 14 so as to be rotated horizontally with respect to the frame 10, to adjust the angle of operation. A driven roll 15 is rotatably mounted in bearings 5 at one end of frame 12 and an idle roll 16 is rotatably mounted parallel thereto on the opposite end of the frame. A conveyor belt 17 is trained about these rolls over the top plate 13 and has a face of vulcanized rubber. A roll 18 of sheet rubber 10 is rotatably supported in notched brackets 19, 19' above the belt.

To provide means for pleating the sheet material as it passes from the roll 18 to the belt 17, a shaft 20 is rotatably mounted in a horizontal position above the belt 17, in brackets 21, 21', fixed to frame 10. A shaft 22 is rotatably mounted parallel thereto on the frame 10 below the swiveled frame 12. A pair of eccentrics 23, 23' are fixed to shaft 22 and their straps 24, 24' 20 are connected by rods 25, 25', to a pair of arms 26, 26' fixed to shaft 20, the arrangement being such that when shaft 22 is rotated, shaft 20 is given a rocking motion. A motor 27 fixed to frame 10, drives shaft 22 through a speed reducer 28, of the worm and gear type, a pair of sprockets 29 and 30, and a chain 31. A pair of radially slotted arms 32, 32', are fixed to shaft 20, one near each end thereof, with their slots parallel to each other and substantially vertical. A 30 pair of cross-heads 33, 33' are slidably mounted in the slots. Each cross-head is formed with a cylindrical socket in its rear face, which rotatably engages eccentric portions 34, 34' of a pair of shafts 35, 35' which shafts are rotatably mounted in brackets 21, 21'. Shafts 35, 35' each have fixed thereto a pinion 36, 36', each of which meshes with a gear sector 37, 37' fixed to shaft 20. The pitch radius of the gear sector is greater than the pitch radius of the pinion. The arrangement is such that as shaft 20 is rocked back and forth, at each end of its swing the cross-heads 33, 33' are moved toward the belt 17 and then retracted therefrom. Mounted between the cross-heads 33, 33' are a pair of bars 38, 38' to each of which is fixed a pressing blade 39, 39'. These blades are adapted to press the sheet material against the face of the belt 17 and to press together the folded material. Preferably the pressing edges of the blades are serrated as shown in Fig. 2. In the case of sheet rubber, the serrations are effective to adhere the folded rubber by a welding or seaming action at spaced-apart, small areas along the fold.

55 In order to provide for adjustment of the over-

lap of the pleats, the ends of the bars 38, 38' are made of semi-cylindrical form to fit cylindrical recesses 40, 40' formed in the cross-heads 33, 33' and are clamped in place by cap screws 41, 41' which extend through arcuate slots 42, 42' in the cross-head. The arrangement is such that each bar 38, 38' may be accurately adjusted with respect to the cross-heads and by adjustment both bars, the blades 38, 38' may be moved farther apart or closer together to change their positions of contact with the belt and therefore the overlap of the pleats.

To provide for intermittent movement of the belt between the formation of successive pleats, 15 roll 15 has a bevel pinion 43, 43' fixed on each end of its shaft, and a shaft 44, 44' journaled in a housing 45, 45' at either end of the roll has a bevel pinion 46, 46' fixed thereto and adapted to drive pinions 43, 43' through idler pinions 47, 47'. 20 Each shaft 44, 44' has a ratchet wheel 48, 48' fixed thereto. A cam 49 may be fixed to shaft 22 at any position along its length. A follower arm 50 is adjustable along the frame 10, and carries a roller 51 which engages the cam. A ratchet 25 lever 52 is pivoted on shaft 44 and carries a pawl 53 which engages the ratchet wheel 48. A connecting rod 54, adjustable as to length, connects arm 50 to arm 52. A tension coil spring 55 is connected between arm 52 and the frame of the 30 machine and holds the follower against its cam. As the frame 12 may be swung to different positions to change the angle of the pleats, the cam 49 and its follower may be shifted to align the cam with the ratchet, and the rod 54 may be adjusted accordingly. At certain positions, the ratchet lever 52 may be changed to pivot on shaft 44' and engage the other ratchet wheel 48'.

To provide for adjustment of the spacing of the pleats, an arm 56 is rotatably mounted on shaft 44 and carries a spring stop pin 57 by which it 40 may be locked in a plurality of positions to a plate 58 fixed to housing 45 and having locking holes 59 formed therein. An arcuate guard 60 is fixed to the arm 56 over the ratchet wheel 48 and under the pawl 53. As the arm 52 is rocked the pawl 53 slides over the guard and engages the ratchet wheel. By adjusting the guard, the angle of intermittent rotation of the ratchet wheel may be adjusted.

50 In the operation of the device a roll of sheet material such as unvulcanized rubber or similar plastic preferably dusted on its surface with starch or similar powdered material to prevent premature adhesion, is placed in brackets 19, 19'. 55 The leading end thereof is passed over bar 38 and under bar 38'. As the machine is set in operation blade 39' presses the sheet against the rubber belt 17 along a single line, as shown in Fig. 6. The rubber sheet adheres to the rubber 60 face of the belt at the line due to the fact that the spreading of the sheet and the belt face at the line of contact due to the pressure spreads the starch grains apart a sufficient amount to expose the adhesive plastic. At the next pressing movement, the leading end of the sheet is carried back over the material adhered to the belt and is adhered to such material along a line parallel to the first line of adhesion, as shown in Fig. 7. The belt with the sheet material thereon 70 is then automatically ratcheted forward and a new pleat is made.

By adjustment of the belt supporting frame, the machine may be set to produce pleats at any angle up to 45 degrees with the direction of travel 75 of the sheet. As the pleated material approaches

the roll 15 it may be stripped from the belt either by the operator or by pulling rolls provided for this purpose. As the adhesion of the sheet to itself is greater than the adhesion of the sheet to the vulcanized rubber belt, the pleats 8 do not pull apart.

After a sheet of material has been pleated with bias pleats, it may be again run through the machine with the conveyor adjusted at a different angle and a second set of pleats may be produced crossing the first set. This provides sheet material of novel, artistic designs.

The invention is applicable to the pleating of sheet materials of various types, and is useful especially to pleat sheet rubber which may be 15 vulcanized after pleating to maintain the pleated and adhered condition permanently.

Variations may be made without departing from the invention as it is defined in the following claims.

I claim:

1. Apparatus for forming sheet material suitable for apparel use, said apparatus comprising a movable member, and means diagonal to the path of motion of the material for successively 25 adhering the material to said member along narrow transverse diagonal zones entirely across the sheet.

2. Apparatus for forming pleated sheet material, said apparatus comprising a movable member, means for adhering the material thereto along narrow transverse zones of the sheet by pressure against the member entirely across the sheet, and means for effecting intermittent movement of the movable member with relation to the 35 adhering means to form the pleats.

3. Apparatus for forming pleated sheet material, said apparatus comprising a movable conveyor, means for temporarily adhering the sheet of the material thereto in a succession of pleats, 40 and means for adjusting the angular relation of the conveyor and the adhering means to change the angle of the pleats.

4. Apparatus for forming pleated sheet material, said apparatus comprising a movable conveyor, a pair of pleating blades each adapted 45 temporarily to adhere the sheet of plastic material to said conveyor by pressing engagement therewith, and means for alternately projecting said blades toward the conveyor in a manner such that the path of one blade intersects the path of the other.

5. Apparatus for forming pleated sheet material, said apparatus comprising a movable conveyor, a pair of pleating blades each adapted 55 temporarily to adhere a sheet of plastic material to said conveyor by pressing engagement therewith, means for alternately projecting said blades toward the conveyor in a manner such that the path of one blade intersects the path of the other, 60 and means for intermittently advancing said conveyor between successive pairs of blade movements.

6. Apparatus for forming pleated sheet material, said apparatus comprising a movable conveyor, a pair of blades adapted to press a sheet of plastic material against said conveyor, means for intermittently moving one of the blades toward and from the conveyor in a direction at an acute angle thereto and for alternately moving 70 the other blade toward and from the conveyor at an acute angle thereto, the paths of movement of said blades crossing each other, and means for intermittently advancing the conveyor between the cycles of the blade movements.

7. Apparatus as defined by claim 4 in which means is provided for adjusting the length of movements of the conveyor.
8. Apparatus as defined by claim 4 in which 5 means is provided for adjusting the positions of the blades with relation to each other.
9. Apparatus as defined by claim 4 in which means is provided to adjust the angle of the blades with relation to the direction of travel of 10 the conveyor.
10. Apparatus for pleating sheet material including an adhesive substance, said apparatus comprising a flat movable supporting surface, and means for forming folds in the sheet material 15 upon said surface including means for adhering together the folds in narrow zones extending entirely across the sheet.
11. Apparatus for pleating sheet material including an adhesive substance, said apparatus 20 comprising a flat supporting surface, a movable element diagonal to the supporting surface contacting the sheet material upon said surface, and means for moving said element to fold the material into pleats diagonal of the sheet and to press the folds of the material into adhering relation 25 substantially across the entire width of the sheet.
12. Apparatus as defined in claim 11 in which the said movable element comprises a blade extending diagonally across the support and the 30 said moving means swings said element fore and aft of the support to effect the folding and pressing of the sheet material.
13. Apparatus for pleating sheet material including an adhesive substance, said apparatus 35 comprising a supporting surface, and means for guiding the sheet material upon said surface in a succession of pleats, said means comprising a pair of elements fixed in parallel non-contacting relation to each other for alternately engaging the sheet at opposite sides thereof and means for moving said elements and guiding means in unison to effect the folding and to adhere together the folded material while temporarily pressing the material against said supporting surface.
- 40 14. Apparatus as defined in claim 13, in which the said moving means is effective to press the material into temporary adhesion with the support in narrow zones extending entirely across the material.
15. Apparatus for making pleated sheet material suitable for apparel use, said apparatus 45 comprising a flat support, movable in a direct path, means for moving the support step by step, a pressing element for temporarily adhering a sheet of plastic material thereto along a narrow transverse zone entirely across the sheet by movement of the element toward the support during 50
- a dwell of the support between successive movements, a second pressing element for folding the sheet and tacking it to itself by a successive movement of the second said element during the same dwell of the support, and means for moving 5 said elements to effect said movements.
16. The method of making pleated sheet material including an adhesive substance, which method comprises forming a sheet of the material in successive folds upon a supporting surface, each 10 fold being made by temporarily adhering the material to the supporting surface along a narrow zone extending across the sheet, then folding the material back upon itself and adhering together the folded material and removing the pleated 15 sheet from the supporting surface.
17. The method of making pleated sheet material including an adhesive substance, which method comprises forming a sheet of the material 20 in successive folds upon a supporting surface, each fold being made by temporarily adhering the material to the supporting surface along a narrow zone extending diagonally across the sheet, then folding the material back upon itself 25 and adhering together the folded material.
18. The method of forming pleated sheet material suitable for apparel use, which method comprises advancing sheet material upon a supporting surface, progressively adhering the sheet material along spaced apart narrow zones thereof entirely 30 across the sheet to the supporting surface, progressively folding the material back upon itself at each of the said zones, adhering the folds to provide pleats, and removing the pleated sheet 35 from the supporting surface.
19. The method of making pleated sheet material which comprises advancing a sheet of material in the direction of its length, and diagonally folding the sheet in a series of pleats by a succession of consecutive pressing movements 40 effected in a direction substantially perpendicular to a face of the sheet.
20. The method of making pleated sheet material which comprises feeding the sheet of material lengthwise to a substantially flat movable supporting surface, moving the supporting surface step by step, guiding the sheet to the support through guide means alternately advanced and retracted with relation to the direction of travel of the supporting surface, and alternately adhering portions of the sheet arriving at such surface to the supporting surface and to the portions of the sheet material already thereon by successive pressing movements directed toward the supporting surface.

ARTHUR E. COLLINS.
